CLAIM

The ornamental design for a flash drive, as shown and described.

DESCRIPTION

FIG. 1 is a perspective view of a flash drive that incorporates our new design.

FIG. 2 is a rear view thereof.

FIG. 3 is a front view thereof.

FIG. 4 is a right-side view thereof.

FIG. 5 is a left-side view thereof.

FIG. 6 is a top view thereof; and,

FIG. 7 is a bottom view thereof.

The broken line showing of the cavity for the USB connector, the USB connector within, and the element within the cavity at the rear of the flash drive are included for the purpose of illustrating unclaimed portions and form no part of the claimed design.
